ILLUMINATED MIRROR

Filed Dec. 23, 1946

UNITED STATES PATENT OFFICE

2,580,258

ILLUMINATED MIRROR

Michael Tarasuk, Detroit, Mich.

Application December 23, 1946, Serial No. 718,028

2 Claims. (Cl. 240—4.2)

1

The present invention pertains to a novel illuminated mirror designed particularly, but not exclusively, for handbag or pocket use.

The principal object of the invention is to provide a device of this character that can be conveniently carried on the person without undue bulk, and that carries a cell and bulb adapted to illuminate the face of the user when desired. The mirror may, however be used in the usual manner without this means of illumination where possible and the cell and bulb may be used as an ordinary flashlight if desired.

In the accomplishment of this object the device comprises a backing having a reflecting surface on one side and a hood slidably mounted on the other side. The hood contains the cell and the bulb, with the latter in such position that it becomes exposed beyond an edge of the reflecting surface on sliding the hood.

The cell and bulb are held within the hood by means of a frame which is so constructed as to hold the end terminals of the bulb and cell in contact with each other. Moreover, the frame engages the other terminal of the bulb in electrical contact therewith. This other terminal, however, is normally out of contact with the other terminal of the cell to hold the circuit open while the bulb is in the non-exposed position relatively to the reflecting surface. When the hood is moved to bring the bulb in the exposed position, the said other terminal of the cell is engaged by a contact member of the backing. The contact member is permanently in contact with the frame through the hood and backing, so that the bulb circuit is completed when this contact engages said other contact of the cell in the exposed position of the bulb.

The invention is fully disclosed by way of example in the following description and in the accompanying drawings in which:

Figure 1 is a front elevation of the device;

Figure 2 is a side view;

Figure 3 is a front elevation of a modification showing the bulb exposed;

Figure 4 is a corresponding side view;

Figures 5 and 6 are sections on the lines 5—5 and 6—6 of Figure 2; and

Figure 7 is a section on the line 7—7 of Figure 1.

Reference to these views will now be made by use of like characters which are employed to designate corresponding parts throughout.

In Figure 1 is shown a mirror 1 enclosed by a backing 2 which is preferably of a conducting material. The backing is formed with a pair of

2

stamped out wings 3 adapted to guide another member on the backing, as will presently appear. Above the wings a tongue or bridging contact 4 of inverted L-shape is stamped out for a purpose that will presently appear. The horizontal leg of the member 4 is the contact portion, and the vertical leg that remains integral with the backing constitutes a resilient connection.

10 A hood 5, also preferably of conducting material, is slidably mounted on the backing 2 by means of a pair of inward flanges 6 formed on the longitudinal edges of the hood and engageable respectively beneath the wings 3. The flanges 6 terminate considerably short of the upper end of the hood, as shown, to permit the hood to be detached from the backing merely by sliding the hood downward on the backing.

15 The hood 5 is adapted to contain a small cylindrical dry cell 7 and is of such length that a bulb 8 may stand upon the cell. In this position the end terminal 9 of the bulb rests on the end terminal 10 of the cell. The metallic casing 11 of the cell constitutes its remaining or ground terminal, and a portion thereof is bared or exposed near the upper end as indicated by the numeral 12.

20 The terminals 9 and 10 are maintained in mutual contact by means of a contact frame or stirrup. This member comprises a pair of parallel longitudinal elements 13 lengthwise of the cell, a foot 14 on which the bottom of the cell rests, and a split ring 15 at the upper end into which the screw base 18 of the bulb is threaded. The foot 14 is insulated on its upper surface by any suitable means, such as a coating 19, in order not to make electrical contact with the lower end of the cell 7.

25 The contact frame 13—15 with the bulb and cell assembled therein in the manner described is readily fitted in the hood 5, with the longitudinal elements 13 accommodated beneath the flanges 6. In practice there is metallic contact between the frame and the hood but this is immaterial since the frame becomes electrically connected to the backing 2 when the wings 3 are received snugly between the sides of the frame and the flanges 6. It now remains to connect the exposed portion 12 of the battery case to the backing in order to complete a circuit through the bulb 8.

30 When the ends of the hood 5 lie substantially at the ends of the backing 2, the exposed portion 12 is unengaged. In order to provide illumination, the hood is slid upward to expose the bulb

8 over the upper edge of the mirror and backing. In this position the tongue or bridging contact 4 engages the exposed portion 12 to complete the circuit previously described. A lens 20 is fitted in the hood in front of the bulb for better projection of light to illuminate the face of the person looking into the mirror, and the interior of the hood may be silvered behind the bulb.

The embodiment shown in Figures 3 and 4 is designed only to expose the bulb above the backing. The lower end 5' of the hood 5 is in a perpendicular plane, so that the user will know by feel which way to push the hood.

Another bridging tongue or contact 21 may be formed beneath the wings 3 to be engaged by another bare spot 22 of the battery case on pushing the hood 5 downward. The bulb 8 becomes illuminated in the manner described and is visible through a suitably shaped opening 23 through the mirror. This is another means of using the device as a flashlight. Both exposures of the bulb may be provided for in a single device, as in Figures 1, 2, 5, 6 and 7. If only the exposure through the hole 23 is desired the contact 4 may be eliminated and the pushing end of the hood made flat. For production purposes, however, both contacts 4, 21 may be retained, although only one is used.

It is apparent that the device is particularly useful in dark places, inasmuch as the illuminated face of the user is visibly reflected in the mirror. The mirror may be of the size ordinarily carried in ladies' handbags, and the hood with the cell and bulb therein adds very little bulk. Thus, the device may be carried in the same manner as a conventional mirror of the same area and is of course equally useful in daylight and in illuminated rooms. Also, the device may be used as a flashlight merely by pushing the hood upward or downward in the manner described.

In the event that polished metal is used for the reflecting surface, the metal itself constitutes the backing for the reflecting surface, and the wings and tongue may be suitably applied to or formed with the mirror body.

Although a specific embodiment of the invention has been illustrated and described, it will be understood that various alterations in the de-

tails of construction may be made without departing from the scope of the invention as indicated by the appended claims.

What I claim is:

5 1. An illuminated mirror comprising a backing, a reflecting surface at one side thereof, a hood slidable on the other side of said backing, a cell and bulb in said hood, each having two terminals, a terminal of the bulb being in contact with a terminal of said cell, said backing and surface having an opening therethrough positioned to expose said bulb, and means for bringing the other terminal of said bulb in contact with the other terminal of said cell on sliding said hood to expose said bulb.

10 2. An illuminated mirror comprising a backing, a reflecting surface at one side thereof, a hood slidable on the other side of said backing, a cell and bulb in said hood, each having two terminals, a terminal of the bulb being in contact with a terminal of said cell, said bulb being movable from a position behind said backing to an exposed position beyond an edge of said reflecting surface on sliding said hood in one direction, said backing and surface having an opening therethrough adapted to expose the bulb on sliding said hood in the other direction, and means for bringing the other terminal of said bulb in contact with the other terminal of said cell on sliding said hood to expose said bulb.

15 MICHAEL TARASUK.
